UNITED STATES PATENT OFFICE.

WILLIAM SCHUMACHER, OF BROOKLYN, NEW YORK, ASSIGNOR OF ONE-HALF TO LOUIS RAHMER, OF SAME PLACE.

PROCESS OF PRINTING IN COLORS.

SPECIFICATION forming part of Letters Patent No. 447,701, dated March 3, 1891.

Application filed March 3, 1890. Serial No. 342,469. (Specimens.)

To all whom it may concern:

Be it known that I, WILLIAM SCHUMACHER, of Brooklyn, in the county of Kings and State of New York, a citizen of the United States, 5 have invented certain new and useful Improvements in Processes of Printing in Colors, of which the following is a specification.

This invention relates to an improved process of printing in colors in such a manner 10 that the well-known character of water-color painting is closely imitated, while the ordinary lithographic stones can be employed for this purpose; and the invention consists of a process of printing in colors which consists 15 of the following steps: first, producing the different tints by means of brush and lithographic inks on thin transparent sheets of celluloid; secondly, transferring the said tints from the sheets of celluloid to the lithographic 20 stones, and, finally, printing from said stones in different colors, so as to reproduce the original painting.

In carrying out my invention I employ thin sheets of celluloid, which are placed one after 25 the other over the water-color or other painting that is to be reproduced in colors, care being taken that the proper register of the sheets with the original painting is retained. One sheet of celluloid is used for each color of 30 the original painting. While the sheet is placed in position on the original painting the special tint is produced in the same by means of a brush and lithographic ink, so that a so-called "wash-tint" is produced, the 35 different portions of which are graduated in proportion to the depth of color in the original painting. When as many sheets as there are colors in the original painting are thus produced, the wash-tints on the same are 40 transferred from the celluloid sheets to as many different lithographic stones. The surface of the stones is grained preparatory to receiving the wash-tints on the transfer-sheets. After the transfer of the wash-tints

is made, the stones are coated with a layer of 45 a solution of gum and after drying washed off, the stones being then rolled up in the usual manner with transfer-ink. The stones are next prepared with gum and acid like a crayon drawing. The wash-tints are broken 50 up into small dots by the raised portions of the grain, so that the tints on the stone are an exact reproduction in dots of the wash-tints on the sheets, they being denser at the heavier parts and thinner at the lighter parts. 55 The different colors are then printed from the stones until a picture in colors is obtained in which the characteristic features and tints of the original painting are faithfully reproduced. 60

In addition to the wash-tints employed, graining or stipple effects may be added to the sheets of celluloid and then transferred to the stones, or they may be produced on the stones in the usual manner. 65

Having thus described my invention, I claim as new and desire to secure by Letters Patent—

The method of printing in colors, which consists in placing successively as many transparent sheets as there are colors in the picture to be copied over said picture and applying to each sheet a wash-tint in lithographic ink corresponding to that part of the original picture to be reproduced by the aid of said 70 sheet, then transferring the several tints to separate lithographic stones having grained surfaces, and then printing the different colors from the separate stones in register to correspond with the parts of the original picture, substantially as described. 75

In testimony that I claim the foregoing as my invention I have signed my name in presence of two subscribing witnesses.

WILLIAM SCHUMACHER.

Witnesses:
